UNITED STATES PATENT OFFICE.

WILLIAM T. DAVIS, OF COMSTOCK, MICHIGAN.

ENGINE GOVERNOR.

Application filed December 31, 1921. Serial No. 526,292.

This invention relates to engine governors, and more particularly to governors especially suited to tractors, wherein a rotor controls movement of the throttle and thus tends to maintain a uniform engine speed.

It is an object of the invention to provide a governor of the character indicated which functions effectively and reliably to control the speed of an engine and which is simple in construction and comparatively inexpensive in manufacturing costs.

Another object is to provide an improved governor of the character indicated which is readily mounted on engines of existing types, without the employment of special tools and with slight alteration in the standard arrangement of the control mechanism thereof.

It is a further object to provide an improved governor which is particularly adapted to control the speed of tractors, is conveniently arranged for application thereto, and results in economies and other advantages in operation thereof.

Still another object of the invention is to provide an efficient device operating from the fan-belt of an engine which serves to maintain a constant engine speed under varying running conditions and by which the power is automatically cut off when the fan-belt breaks or is displaced.

Other objects will be in part obvious and in part pointed out hereinafter in connection with the following description of the accompanying drawings which illustrate a typical but preferred embodiment of the invention, and in which

Figure 1 is an elevation showing the application of the improved governor to a standard form of tractor;

Fig. 2 is a plan view of the governing mechanism shown as operating at normal speed;

Fig. 3 is a fragmentary longitudinal central section through the governor casing showing rotatable parts at rest;

Fig. 4 is a sectional view taken approximately on the line 4-4 of Fig. 3 looking in the direction indicated by the arrow; and

Fig. 5 is a detail of one of the parts.

Referring to Fig. 1 for an understanding of the general arrangement of the governing mechanism in use, a tractor of a standard type is shown, for which the illustrative embodiment of the invention herein described is especially adapted, although it is to be

understood that the invention is applicable to any similar type of machine. The tractor shown is provided with a standard gasoline engine designated generally by the numeral 1, a gas tank 2, a carburetor 3, a throttle valve 4 with throttle lever 4' for controlling the admission of fuel to the engine cylinders, a fan 5 and a fan-belt 6 for operating the same.

The principal operating parts of the governing mechanism are contained within a cylindrical housing or casing 7 secured in position adjacent the cylinder-head of the engine, supported and journaled in the walls of which is a shaft 8 having a projection with a wheel 9 adapted to be rotated by the fan-belt 6. Rotation of the shaft 8 actuates governing weights within the housing and these weights regulate the position of the throttle valve through lever 4 by an intermediate train of connections, as will be described. The throttle lever may also be directly controlled manually from the operator's station at A by means of a rod 10 held by a bracket 11 conveniently mounted on the dash of the tractor.

Referring more particularly to Figs. 2 and 3, the housing 7 has a projecting plate or rib 12 adapted to be attached over the cylinder head of the engine by bolts 13. For convenience in assembly these bolts may also serve to secure the cylinder head of the engine in place the bolt holes in the plate 12 being spaced the same as the cylinder-head bolts. Within the housing a sleeve 14 is fixed to the shaft 8, as by means of a set screw 15 and a second sleeve 16 is mounted loosely on the shaft 8 so as to slide longitudinally thereon. A governor weight constituting the sensitive governing or speed responsive element is pivotally mounted on the sleeve 14 by means of a pin 17, and consists of two comparatively heavy end-portions 18, which function as governor balls, connected by side plates 19 straddling the sleeve 14. A link 20 connects the governor weights to the slidable sleeve 16, being pivotally connected to weights and sleeve by pins 21 and 22 respectively. A heavy coil spring 23 connects the pin 21 to a part of the stationary sleeve 14, and tends to resist pivotal motion of the governor weights from the position of Fig. 3 as the shaft 8 rotates.

The shaft 8 has a hollow portion concen-

tric with the shaft and longitudinally aligned slidable plungers 24 and 25 are mounted in said hollow portion, the plunger 24 being provided with a transverse pin 26 extending through a guiding slot 27 in the shaft and disposed to contact with the end of the slidable sleeve 16. A lever 28 is pivotally mounted on the plate 12 and is connected to the plunger 25 by means of a pin 29. It will be obvious that as the shaft 8 is speeded up the governor weights are moved radially from the shaft by centrifugal force tending to bring the weights into a plane at right angles to the shaft, which movement is communicated to the lever 28 by the slidable connections described.

In the form shown outward movement of the lever 28 is resisted by a compression spring 30 encircling a stationary bolt 31 extending through an opening in lever 28 and secured in position on a part of the casing. The bolt is attached in position by being passed through an opening in a projecting bracket 32 on the casing, and a plate or trigger 33 pivotally mounted on the bracket 32 holds the bolt in position by engagement within a slot 34 therein. A tension spring 35 serves to hold the trigger 33 in engaging relationship under normal conditions.

30 A bell-crank-lever 36 pivotally mounted at 36' on the plate 12 has one arm 37 connected to the free end of the lever 28 by means of an adjustable speeder screw 38 and a threaded bracket 39 co-operative therewith and 35 pivotally mounted on the free end of the lever 28. A spring 40 surrounding the screw 38 is compressed between the arm 37 and a pin 40' on the bolt and tends to separate the ends of the levers and thus serves to assure 40 tight adjustable connections therebetween. The control rod 10 previously mentioned is connected to this screw 38 through the speeder head 38' and is adapted to rotate the same when it is desired to adjust the relationship 45 between the ends of the levers 36 and 28. Bodily movement also of the lever 28 to control the throttle may be accomplished by manually moving the rod 10 longitudinally. The other arm 41 of the lever 36 is connected 50 to the throttle lever 4 by an intermediate link 42.

The operation of the device thus far described should be clear from the foregoing. Assume that the engine is running at normal 55 speed and that the relationship between the two levers 28 and 37 of the governor has been adjusted to hold the throttle valve in position to maintain this speed. If then, for example, the tractor comes to a decline 60 in its course, the shaft 8 will tend to speed up, thereby throwing the weights outwardly under centrifugal force, and rocking the lever 28 through the connections within the housing described. Pivotal movement of 65 the lever 28 to the left in Fig. 2 rocks the

bell-crank-lever correspondingly and thus moves the throttle lever 4 in a closing direction, which operates to impede the flow of fuel to the engine cylinders and thus automatically to decrease the engine speed. 70 Under the reverse conditions, that is, when the course of the tractor is obstructed, a reverse movement of the governor weight is occasioned, whereupon a reverse movement of the levers operates to open the throttle 75 valve and to speed up the engine. In this manner a uniform speed under all conditions is maintained. As mentioned, the position of the throttle lever 4 may be changed instantly when desired by bodily movement of the rod 10, irrespective of the condition of the governing mechanism. The governor is particularly desirable and effective when the tractor is employed for belt work, such, for example, as driving a wood saw.

Provision is also made in the form shown for automatically cutting off the inflow of gas and thereby stopping the engine and avoiding overheating when the fan-belt breaks or becomes displaced from position. 80 To accomplish this result the bolt 31 is adapted to be disengaged from the bracket 32 and its separation is assisted by a spring 43 which is normally compressed between the bracket 32 and a collar 44 on the bolt 31. 85 An idler wheel 45 is mounted on an arm 46 which is secured to a rod 47 rotatably mounted on a bracket 48 fixed to the housing 7. Under normal conditions the idler wheel 45 rests by gravity on and is supported by the fan-belt 3. The rod 47 has an angularly disposed end forming an arm 49 lying adjacent the upper end of the trigger 33. When the belt breaks, the idler wheel 45 drops under its own weight and forces the arm 49 against the co-operating end of the trigger 33 (Fig. 4), thus effecting pivotal motion of the trigger against the tension of spring 35 sufficient to disengage the trigger from the slot 34 of the bolt 31. When the bolt is thus freed the spring 43 operates to separate the bolt from the bracket 32, the collar 44 engaging lever 28, resulting in pivotal movement of the latter outwardly from the position of Fig. 2, the spring 30 also assisting in this movement. This action operating through the bell-crank-lever 36 closes the throttle valve and stops the engine instantly.

By the above described mechanisms an 105 efficient governor is provided whose rotating parts are enclosed in dust-proof condition within a cylindrical housing conveniently attached on the cylinder of the engine, and adjustment is allowed in the train of levers 110 so that the speed of the engine is capable of automatic control under varying conditions of service, while the degree of regulation is instantly adjustable from the operator's station A through the rod 10 and the speeder screw 38. For belt work the speed is auto- 115 120 125 130

5 matically regulated saving the time of a man otherwise required for this purpose. The movable parts of the governor are supported on the bracket conveniently secured to the 10 tractor engine providing a unitary structure which is capable of installation on the tractor easily and quickly and without the services of a skilled mechanic. All that is necessary 15 to connect the governor for operation after the governor bracket is bolted in position on the engine and the idler 45 and pulley 9 placed in contact with the fan-belt, is to connect the link 42 of the bell-crank lever to the throttle valve lever 4, and to place the manual control 20 and adjusting rod 10 in position. Since the governor parts are usually assembled with the bracket when sent out to the user, it will be seen that the installation of the device will be a simple matter. The arrangement 25 of plungers 24, 25 concentric with the governor shaft 8 provides a convenient and efficient mechanism for transmitting the movement of the governor balls to the engine throttle assuring accurate control under operating conditions.

30 As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

35 It is also to be understood that the language used in the following claims is intended to cover all of the generic and specific features of the invention herein described, and all statements of the scope of the invention which, as a matter of language, might be said to fall therebetween.

40 Having described my invention, what I claim as new and desire to secure by Letters Patent, is:

45 1. In a governor for engines, in combination, a housing, a shaft rotatably mounted in said housing and carrying a governor ball within said housing, means for rotating said shaft from a moving engine part, means for 50 operatively connecting the engine throttle with said ball, manually operable throttle adjusting and emergency throttle control means connected with and operable upon said governor mechanism, said emergency control automatically moving said throttle toward closed position upon failure of said first mentioned means.

55 2. In a governor for engines, in combination, a rotatable governor member operatively connected to vary the fuel to the engine cylinder, manually operable throttle adjusting and emergency throttle control means connected with and operable upon said governor mechanism, means whereby the cooling 60 fan operating mechanism imparts rotating

movement to said governor member, said emergency control automatically decreasing the fuel flow to the engine upon failure of said fan operating mechanism.

3. In a governor for power driven tractors, 70 in combination, a throttle operating device, mechanism for automatically controlling the fuel supply to the engine of the tractor in proportion to the load thereon, manual means operable from the operator's station 75 for altering the fixed adjustment between said throttle device and said automatic mechanism and to independently control the fuel supply, means for controlling said automatic mechanism from the tractor engine, 80 and automatic means for reducing the fuel supply to the engine upon failure of said last mentioned means.

4. In a governor for power driven tractors, 85 in combination, a throttle operating device, mechanism for automatically controlling the fuel supply to the engine of the tractor in proportion to the load thereon, manual means operable from the operator's station 90 for altering the fixed adjustment between said throttle device and said automatic mechanism and to independently control the fuel supply, means for driving said automatic mechanism directly from the fan belt of the engine, and means for automatically 95 reducing fuel supply to the engine upon failure of said fan belt.

5. In a governor for power driven tractors, 100 in combination, mechanism for automatically controlling the fuel supply to the engine of the tractor in proportion to the load thereon, and manual means operable from the operator's station for adjusting the said automatic mechanism for different degrees of fuel regulation, said manual means being 105 operable independently of its adjusting action to control fuel supply independently of said automatic mechanism.

6. In a governor for power driven tractors, 110 in combination, a bracket adapted to be bolted to a fixed part of the tractor engine, a pair of yieldingly connected levers pivotally connected to said bracket and arranged to control fuel supply to said engine, a speed responsive governor element carried by said bracket and operatively connected to said levers, an adjustable connection between said levers for adjusting the said fuel control by 115 said governor and operating connections controllable from the operator's station for operating said adjustable connection for controlling said fuel supply independently of control by said governor element.

7. In a governor for power driven tractors, 125 in combination, a bracket adapted to be bolted to a fixed part of the tractor engine, spaced levers pivotally connected to said bracket, a speed responsive element carried by said bracket and operatively connected to one of said levers, the other lever being oper- 130

atively connected to the engine throttle, an adjustable operating connection between said levers, and means operable from the operator's station for adjusting said adjusting connection.

8. In a unitary governor element for tractor engines, including in combination, a bracket adapted to be bolted to the engine frame, a speed responsive element carried by 10 said bracket, a driving element for said speed responsive element adapted to lie in position to be engaged by a modified fan belt of the engine when the bracket is bolted in position, a lever carried entirely by said bracket and 15 lying in position for connection to the engine throttle when the bracket is bolted in position, and operative connections between said lever and said speed responsive element.

9. In a unitary governor element for tractor engines, including in combination, a bracket adapted to be bolted to the engine frame, a speed responsive element carried by 20 said bracket, a driving element for said speed responsive element adapted to lie in position to be operated by a modified fan belt of the engine when the bracket is bolted in position, a lever carried by said bracket and lying in 25 position for connection to the engine throttle when the bracket is bolted in position, and operative connections between said lever and 30 said speed responsive element, means for urging said lever toward throttle opening position, a member carried by said bracket and lying in position to cooperate with the 35 fan belt when the bracket is bolted in position, and means controlled by said member when the fan belt brakes for urging said lever toward throttle closing position.

10. In a governor for power driven tractors, in combination, a bracket adapted to be bolted to a fixed part of the tractor engine, a pair of yieldingly connected levers pivotally connected to said bracket and arranged 40 to control fuel supply to said engine, a rotatable governor element carried by said bracket and operatively connected to said levers, and an adjustable connection between 45 said levers for adjusting the fuel control by said governor.

50 11. In a governor for power driven tractors, in combination, a bracket having a rib with openings spaced to correspond with the spacing of the cylinder head bolts whereby said bracket may be secured in position 55 by said bolts, a housing carried by said rib and having a speed responsive element mounted therein, a shaft for operating said speed responsive element mounted in said housing and having a projecting part carrying 60 a pulley lying in position to contact with the modified fan belt when the bracket is bolted in position, and operative connections mounted on said bracket and disposed in 65 position for attachment to the engine throttle, and means whereby said operative connections may be adjusted to vary the degree of control by said speed responsive element or independently operated for manual control of the throttle.

12. In a governor for power driven tractors, in combination, a bracket having a rib with openings spaced to correspond with the spacing of the cylinder head bolts whereby said bracket may be secured in position 70 by said bolts, a housing carried by said rib and having a speed responsive element mounted therein, a shaft for operating said speed responsive element mounted in said housing and having a projecting part carrying a pulley lying in position to contact with the modified fan belt when the bracket is bolted in position, spaced levers permanently connected to said bracket and disposed on the remote side of said housing 75 from the pulley, one of said levers having an arm lying in position for connection to the engine throttle when the bracket is bolted in position and the other lever being operatively connected to said speed responsive 80 element for controlling said throttle.

13. In a governor for power driven tractors, in combination, a bracket having a rib with openings spaced to correspond with the spacing of the cylinder head bolts whereby said bracket may be secured in position 85 by said bolts, a housing carried by said rib and having a speed responsive element mounted therein, a shaft for operating said speed responsive element mounted in said housing and having a projecting part carrying a pulley lying in position to contact with the modified fan belt when the bracket is bolted in position, spaced levers permanently connected to said bracket and disposed on the remote side of said housing 90 from the pulley, one of said levers having an arm lying in position for connection to the engine throttle when the bracket is bolted in position and the other lever being operatively connected to said speed responsive 95 element for controlling said throttle.

14. In a governor for power driven tractors, in combination, a bracket having a rib with openings spaced to correspond with the spacing of the cylinder head bolts whereby said bracket may be secured in position 100 by said bolts, a housing carried by said rib and having a speed responsive element mounted therein, a shaft for operating said speed responsive element mounted in said housing and having a projecting part carrying a pulley lying in position to contact with the modified fan belt when the bracket is bolted in position, spaced levers permanently connected to said bracket and disposed on the remote side of said housing 105 from the pulley, one of said levers having an arm lying in position for connection to the engine throttle when the bracket is bolted in position and the other lever being operatively connected to said speed responsive element for controlling said throttle.

15. In a governor for power driven tractors, in combination, a bracket having a rib with openings spaced to correspond with the spacing of the cylinder head bolts whereby said bracket may be secured in position 115 by said bolts, a housing carried by said rib and having a speed responsive element mounted therein, a shaft for operating said speed responsive element mounted in said housing and having a projecting part carrying a pulley lying in position to contact with the modified fan belt when the bracket is bolted in position, and operative connections mounted on said bracket and disposed in 120 position for attachment to the engine throttle, and means whereby said operative connections may be adjusted to vary the degree of control by said speed responsive element or independently operated for manual control of the throttle.

25

30

35

40

15. In a governor for power driven tractors, in combination, a bracket having a rib with openings spaced to correspond with the spacing of the cylinder head bolts where-
5 by said bracket may be secured in position by said bolts, a governor ball rotatably mounted on said bracket, operative connec-
tions controlled by said governor balls for controlling the fuel supply to said engine,
10 and manual means connected to said opera-
tive connections for controlling said fuel supply independently of said governor ball, said manual means being also operable to adjust the fuel controlling connections for
15 varying the degree of fuel control by the governor.

16. In a tractor engine, in combination, automatic means including two yieldingly connected levers for controlling the flow of
20 fuel to the engine including resilient means biased to urge said fuel controlling means in a direction to increase fuel flow, and means operative on the failure of the con-

nctions for driving the cooling fan of the engine to overcome said bias.

17. In a tractor, in combination, a gover-
nor having a rotary element driven from the tractor engine, connections from said rotary element to the engine throttle, and
25 rotary and longitudinally movable adjust-
ing means for said connections operable from the operator's station, said adjusting means being also adapted to control said en-
gine throttle independently of said governor.

18. In a device of the character described, in combination, a shaft adapted to be rotat-
ed by an engine, a governor ball mounted on said shaft, a lever connected to said
governor ball and to the throttle lever of
30 the engine, and means for operating said lever independently of said ball, including a manually operable rod adapted to be ro-
tated to adjust said lever and adapted to be moved bodily to operate said lever.

In testimony whereof I affix my signature.
WILLIAM T. DAVIS.
